**METHOD OF MAKING CONTACT MEMBERS
FOR CROSSBAR SWITCH**

Andrew W. Vincent, 65 Aberdeen St., Rochester 11, N.Y.
Filed July 18, 1960, Ser. No. 43,422
11 Claims. (Cl. 29—155.55)

The present invention relates to a cross bar switch for connecting various electric conducting members to each other in various possible combinations, and more particularly to an improved method of forming contact members of a cross bar switch.

This application is a continuation-in-part of my U.S. patent application Serial No. 645,609, filed March 12, 1957, now Patent No. 2,950,350, granted August 23, 1960.

One object of the present invention is to provide an improved method of making the contact members of the channel strip, or link bar, or cross conductor, of a cross bar switch.

Another object of this invention is to provide a method for making improved contact members for the channel strip, or link bar, or cross conductor, of a cross bar switch.

Still another object of the invention is to provide improved channel strip, link bar or cross conductor construction for a cross bar switch.

Other objects of this invention will be apparent hereinafter from the specification, the accompanying drawings, and the appended claims.

In the drawings:

FIG. 1 is a fragmentary perspective view of a cross-bar switch having contact members made in accordance with an embodiment of this invention;

FIG. 2 is a fragmentary perspective view of a portion of a channel strip or link bar or cross conductor of this switch having contact members constructed in accordance with and by one embodiment of this invention;

FIG. 3 is a perspective view of a portion of the line strip or line conductor of the cross bar switch;

FIG. 4 is a perspective view of a modified cross conductor, channel strip, or link bar, made according to this invention;

FIG. 5 is a plan view on an enlarged scale, illustrating one stage in the manufacture of a channel strip, link bar, or cross conductor according to this invention;

FIG. 6 is a section on the line 6—6 of FIG. 5, looking in the direction of the arrows;

FIG. 7 is a cross section on the line 7—7 of FIG. 5 looking in the direction of the arrows; and

FIG. 8 is a fragmentary sectional view illustrating another step in the manufacture of the channel strip, link bar, or cross conductor.

The type of cross-bar switch, to which the present invention is applied, is disclosed in my United States Patents No. 2,731,516, granted January 17, 1956, and No. 2,729,706, granted January 3, 1956, and in my pending U.S. application Serial No. 645,609 above referred to, and reference may be had to those patents and application for a more detailed disclosure of this general type of switch. Suffice it to say that a cross bar switch has a desired number of line conductors arranged in banks extending parallel to each other, and any desired number of cross conductors, or link bars, which alternate with the line conductors and cross these at right angles. These cross conductors or link bars are in the form of channel strips. Electrical contacts are made at selected points where the link bars cross the line conductors, by moving selected portions of the line conductors, as by pushers that move at right angles to both the line conductors and the link bars, to bring the selected portions of the line conductors into electrical contact with the link bars.

The type of switch to which the invention relates is

2

shown generally in FIG. 1. This switch comprises a plurality of line plates 31 which extend from front to rear approximately in vertical planes arranged parallel to and spaced laterally from each other. These line plates 31 have suitable stiffening flanges 33 extending laterally at their top edges, and similar stiffening flanges (not shown) at their bottom edges. The line plates 31 are fastened at front and rear to front and rear frame members, of which one is shown fragmentarily at 25.

10 In addition to the physical connection of the front frame bars with the rear frame members by means of the line plates 31, the front and rear frame members are also connected to each other by a flange plate 41 which is shown only fragmentarily and which extends from front to rear along the right hand edge of the structure near the top thereof. This plate serves as a support for magnets which operate the selector or interposer mechanism of the switch.

Each line plate 31 is provided with a number of openings or windows in the form of wide vertical slots 61, the 20 number of such slots being equal to the number of banks of cross-conductors which are to be employed. On one side of each line plate 31 (the far side when viewed in FIG. 1), there is fastened a plate 63 of insulating material, which serves to close the windows 61 except for apertures 25 65 formed in the insulating plate 63, which apertures are equal in number to the number of cross conductors or link bars mounted on the line plate 31. These apertures receive and tightly hold the cross conductors, or link bars, or channel strips 67 which extend through these apertures 30 approximately perpendicular to the line plates 31.

Line conductors, which are adapted to electrically connect with the contact portions of the link bars 67, extend longitudinally along the line plates 31, at elevations slightly above the respective link bars 67. Each line conductor 35 comprises a continuous strip 71 (FIG. 3) of thin, flexible, resilient metal, suitably connected to a stationary terminal at its front end and to a similar terminal at its rear end. The fastening of the ends of each line conductor 71 to the stationary terminals serves to anchor each line conductor 40 against longitudinal movement and to hold the ends thereof in a given horizontal plate just above the top of the link bar 67 with which the line conductor is intended to operate.

At various intervals throughout its length (corresponding to the intervals at which the banks of crossing link bars are spaced from each other) each line conductor 71 is provided with a flexible, resilient arm 73 (FIGS. 1 and 3) that extends first laterally relative to the length of the main strip 71 and then a substantial distance in a general direction parallel to the main strip 71. Each arm 73 has a wider free end 75 formed with a slight upward tilt relative to the arm 73, from which a reversely projecting finger 77 extends. There is one of these arms 73 for each of the link bars 67 with which the line conductor 71 is to make selective contact.

55 On the face of each line plate 31 opposite from the insulating plate 63 (that is on the near face when viewed in FIG. 1) the line plate 31 is provided in each space between two successive windows or slots 61, with a metal plate 81, which has parts near its top for supporting and guiding the selector mechanism and the contact closing mechanism, as further described below. Each line plate also has a lateral projection 83 near its top, and a similar lateral projection (not shown) near its bottom, on each 60 of which there is fastened a leaf spring 85 of resilient metal, which is longitudinally slotted to receive in the slot thereof, a pusher 87 formed of stiff insulating material. In FIG. 1, only one of the springs 85 is shown for clearness in illustration. Each pusher has a hook 89 extending over the free end of the spring 85, and a similar hook (not 65 shown) extending over the free end of the similar spring at the bottom of the structure. By means of these hooks 70

extending over the springs, the top and bottom ends of each pusher 87 are supported and guided. The springs tend to raise each pusher to its uppermost position, but the pusher is capable of limited vertical downward movement, flexing the springs. Since the springs are flexible vertically but not horizontally, they serve not only as supports but also as guides accurately holding the pushers 87 in alignment and preventing lateral displacement thereof.

Each pusher 87 extends vertically through the slots 91 (FIG. 3) between the main spring arms 73 and the fingers 77 of vertically aligned line conductors, whereby the line conductors are guided against shifting laterally out of proper alignment. Each pusher 87 has, at an elevation just above each of the line conductors 71 associated therewith, a projecting lug 93 (FIG. 1) having a downwardly faced foot 95.

The underside of each portion 75 of the line strip or line conductor is provided with a contact member 101 firmly secured, as by welding, to the member 75 and extending in a general direction crosswise of the conductor 71 and crosswise of the line plate 31 on which this conductor is mounted. Each of the contact members 101 is adapted to cooperate with a pair of contact members 103 and 105 suitably secured, as by welding, to the top surfaces of a pair of spring tongues 107 and 109 (FIGS. 1, 2 and 3) formed on a link bar 67. When a portion 75 of a finger 73 is slightly depressed (by downward movement of a pusher 87) from its normal elevation, the flat bottom face of the contact member 101 of that finger 73 comes down against the flat top surfaces of and makes electrical contact with the two contact members 103 and 105 therewith.

The actuator mechanism of the crossbar switch comprises, for each line plate 31, a line magnet (not shown) and a lever 131 actuated thereby. At its free end each lever 131 enters an opening 141 at the rear end of an actuator or hold bar 143 formed of relatively rigid metal and extending along the top of a line plate 31. Each bar 143 is guided for limited longitudinal movement by upstanding guide tongues 145, 147 which engage opposite sides of the bar. These are formed on the plates 81, so that each bar 143 is guided at a number of different points along its length.

At its front end (the left end as viewed in FIG. 1), each actuator bar 143 has a small opening 151 in which is received the laterally-extending end of finger 153 of an upstanding leaf spring member 155 that is secured to the associated line plate 31 near the front end thereof. This spring tends to draw the bar 143 resiliently forwardly, and holds the rear end of the bar constantly in firm engagement with the magnet lever 131. A stationary ear 161, which extends laterally from an upstanding rigid post 163, engages in the opening 141 at the rear of each actuator bar 143, and serves with the spring finger 153 to hold each actuator bar at the desired elevation.

The horizontal motion of an actuator bar 143 is transmitted into a vertical motion of the associated pushers 87 through a rocker comprising a slotted main or bottom flange 181, and two integral upstanding portions 185 and 187. Each rocker is hingedly connected to a stationary lug 171 by a hinge including spring member 197 as more particularly described in my application Serial No. 645,609 above-mentioned. The pusher springs 85 exert upward force tending to move the free end of the flange 181 of the rocker upwardly to an extent limited by contact of this end with a fixed stop 207 formed as an integral laterally bent lug on the plate 81. The same extensions 89 on the pushers 87, which form the hooks engaging over the springs 85, have their top surfaces engaged against the under faces of the free ends of the rocker flanges 181 so that the fixed stop 207 determines not only the upper position of the rocker flange 181 but also the upper position of the pusher 87, and any downward swinging movement of the rocker flange 181 will cause downward cor-

responding movement of the pusher 87. Each pusher 87 extends upwardly through the slots 183 in the associated rocker flanges 181, and is guided thereby.

The motion of each actuating bar 143 is transmitted to the associated rockers by a clip 211. Extending across the switch structure, near the top thereof, are a number of selector wires or rods 231 equal in number to the number of vertical stacks or banks of link bars, one selector wire or rod 231 being for use with each individual stack or cross conductor.

At its left end each selector wire 231 is anchored to a cross tension spring (not shown) which in turn is anchored to a stationary part of the frame. The opposite or right hand end of each selector wire 231 is connected to a selector magnet (not shown). There is a selector magnet associated with each selector wire 231; and when any one of the selector magnets is energized, it will operate to pull the selector wire 231 connected with that magnet against the resistance of the cross tension spring which is associated with the selector wire.

Mounted on each selector wire are several interposer assemblies, one for each line plate 31. Thus, if the switch structure includes ten line plates, there will be ten interposer assemblies on each of the several selector wires 231.

Each selector wire 231 is guided in a horizontal slot 261 (FIG. 1) formed in the upper portion of each plate 81 and opening at its forward end at the top edge of the plate 81. A little to the left of each plate 81 and its associated actuating bar 143, in the space between this bar and the next adjacent actuating bar of the next adjacent line plate 31, there is an actuator assembly comprising a coil spring 265 and an interposer, one part of which is denoted at 279 in FIG. 1. Each interposer is frictionally connected to the associated coil spring 265 which is necked down for this purpose. A portion of the interposer extends through a guide slot or pocket formed in the clip 211 which is secured to the associated rocker 185, 187 and has a portion which is engaged against the left side of the associated actuating bar 143 when the interposer is moved rightwardly into operative position.

The bottom edge of each actuating bar 143 has a notch 301 in it in the vicinity of each rocker. The forward end 303 of each notch constitutes the abutment surface, or force-transmitting part of the actuating bar, for moving the selected rocker upon longitudinal movement of the actuating bar.

When one of the selector magnets is energized to draw its selector wire rightwardly, all the interposers mounted on this selector wire are moved rightwardly so that the effective part of the interposer is brought between the parts 211 of the rocker and the abutment surface 303 of the actuating bar 143. This effective, or force-transmitting part of the interposer almost fills the space between the parts 211 and 303 when the actuating bar 143 is in its relaxed or forward position. Therefore, if, while the interposer is held in effective position, the actuating bar 143 is moved rearward by energization of its actuating magnet, the shoulder 303 of the actuating bar will push rearwardly against the interposer, transmitting force through the interposer and swinging the associated rocker on its hinge, thus depressing the rear end of the rocker flange 181 to cause downward movement of a pusher 87 to close the vertical stack or bank of switches at this particular crossing point by bringing the contacts 101 of the line conductors 71 of the stack into engagement with the contacts 103, 105 of the crossing link bars 67.

When a particular vertical stack or bank of line conductors 71, mounted on one of the line plates 31, is to be electrically connected to a particular vertical stack or bank of link bars 67, the selector magnet for this particular bank of link bars is first energized to actuate the individual selector wire 231 relating to this particular bank of link bars. All of the interposers 279 mounted on this actuated wire 231 will thus be moved into effective position. A brief instant after the selector magnet is ener-

gized, the particular actuating magnet for the particular line plate 31 in question will be energized, thereby causing rearward longitudinal movement of the actuator bar of this particular line plate 31. This will rock the rocker 181, 185, which is located at the crossing of the particular selector wire 231 and the particular actuator bar 143, thereby depressing the pusher 87 of this particular crossing, and connecting all of the line conductors 71 of this particular line plate 31 with the respective link bars 67 of the selected bank of link bars. But the other rockers 10 on the same line plate 31 will not be actuated because the interposers 279 for these other rockers have not been shifted to operative position. Other rockers on other line plates 31 will not be moved regardless of whether or not the interposers have been moved to effective position, because the actuating bars 143 of these other line plates will not be moved. The actuating bar 143, which has been moved to operative position, will be maintained in operative position to hold the contacts closed, as long as its actuating magnet remains energized, even though the magnet that moves the selector wire 231 is deenergized. As long as the actuating magnet remains energized, there can be no further actuation of any of the switches of this particular line plate 31. However, the switches on any other line plate 31 are available for actuation, either in connection with the same bank of link bars or in connection with another bank of link bars.

The above construction is illustrated and described in full detail in my copending application Serial No. 645,609, above mentioned. The present application relates specifically to the structure of the link bars and to a method of manufacturing the link bars.

Each link bar 67 is formed with a plurality of pairs of flexible tongues 107 and 109 that are spaced from one another longitudinally of the link bar. The contacts 103 and 105 are carried by these tongues. The link bars are of inverted channel shape; and the tongues 107 and 109 are integral with the tops of the inverted channel bars. Each channel bar 67 itself is made of beryllium copper. In a first punching operation, the side edges of the tongues 107 and 109 are sheared from the tops of an inverted channel 67, and the two tongues 107 and 109 together (not yet cut apart) are arched upwardly out of the plane of the base flange, leaving a bridging portion 108 which integrally connects the two tongues 107 and 109 together. In this same stamping operation, the bridging portion 108 is preferably cut adjacent its sides partly away from the tongues 107 and 109 and bent down to form the two tangs 111. Then the channel 67 is heat treated to harden the metal to the desired degree. For example, the channel may be heated to approximately 700° F. and held at this temperature for approximately one hour, or may be heated to approximately 600° F. and held at this temperature for approximately two hours. After heating the channel is allowed to cool slowly in air to room temperature. Any known form of heat treatment of beryllium copper may be employed, either in addition to, or as a substitute for the specific treatment mentioned above as an example, the point of this phase of the invention being that this heat treatment (whatever its exact nature) of beryllium copper, which both hardens and stress relieves at the same time, takes place while the two tongues 107 and 109 are still integrally connected endwise to each other by the bridge 108 to form parts of a single curved member or arch which at both ends is integral with the main flange or top of the inverted channel member.

This arched formation of the tongues and bridge is inherently stable, so that these parts maintain, during heat treatment, the correct shape to which they were formed during the first punching operation. Experience shows that if the two tongues were cut apart before the heat treatment, so that each was supported only in cantilever fashion, there is great likelihood of warping or distortion during the heat treatment, unless the tongues are

held in place by jigs or fixtures. Any such distortion is extremely undesirable in electrical switch parts such as these, where the parts must be held to close tolerances, to permit the relatively movable members to make proper contact with each other despite the slight movement which is desirable when the switch is to be closed, and to prevent false closing or false contact when the switch is intended to be open. The integral arch formation, during the heat treating step, holds the spring fingers in the desired position, without the need of jigs.

When the heat treatment, which relieves the stresses set up in the metal during the punching and forming step, is finished, the channel 67 is subjected to a second punching operation, to separate the two tongues 107 and 109 from each other at the center of the arch by cutting out the bridge portion 108 so that the two tongues can move up and down independently without rubbing endwise on each other. This step is accomplished according to this invention by using a pair of punches 113 and 114 which have active faces consisting of an inclined portion and a plane tip portion. The inclined portions 116 and 118 of the two punches are parallel and complementary to each other; and the plane tip portions 121 and 122 of the two punches are parallel and formed at right angles to the direction of operating movement of the two punches. The punches are disposed so that their plane portions 121 and 122, respectively, engage, on their punching strokes, the tongues 107 and 109, respectively, adjacent the bridging portion 108 connecting the tongues. On the punching strokes, then, the inclined surfaces 116 and 118 of the two punches twist and break out the bridge portion 108 from the tongues 107 and 109, thereby separating the tongues. The cuts, which are made when the tabs 11 are formed, define 30 breaking lines so that when the bridge portion 108 is twisted, it will break away cleanly from the tongues 107 and 109. The partial shearing of the metal provides a notch effect where the tabs join the tongues at the inner ends of the tabs, and acts as would a scored line, pre- 35 disposing the metal to break straight across the ends of the bridge portion 108.

As soon as the bridging part 108 is twisted out from between a pair of tongues 107, 109, through their resiliency the tongues will spring back to position to be 40 at the same height and inclination which they had before severance of the bridge from the tongues. Thus they will occupy the same positions which they occupied upon completion of the heat-treatment.

After heat treatment and preferably after severance 45 from one another of the tongues of a link bar, the contact members 103, 105 are brazed on the adjacent ends of each pair of tongues. The contact members 103, 105 are preferably made of gold, although palladium may be used also. Either metal gives long life to the 50 make-and-break contacts involved.

The contact members 103 and 105 are elongated in the direction transverse to the length of the channels 67 and parallel to the length of the adjacent line plate 31 and line conductor 71. Thus, these two contact members lie at right angles to the length of the contact member 101 on the line conductor.

When a portion 75 of a line conductor is at its normal elevation, the contact member 101 of that portion 75 is spaced slightly above the normal elevation of the co- 60 operating contact members 103 and 105, so that the switch at this point is open. When a portion 75 of a line conductor is slightly depressed (by downward movement of the insulating pusher 87) the contact member 101 of that portion 75 is brought down firmly against the top surface of both of the cooperating contacts 103 and 105 on the link bar 67, making firm electric contact with both of them, and thus closing the switch at this point to connect the line conductors 71 electrically with the link bar 67. The use of the two contact members 103 and 70 75 105, mounted for independent resilient movement on

their respective tongues 107 and 109, makes the switch closing contacts more reliable and certain, since a speck of dust on one of the contact members 103 and 105, will not prevent the other from making proper contact with the member 101.

The line conductors 71 may be either made of nickel silver alloy or beryllium copper (preferably the latter). The contact members 101 of the line conductors may be made of gold or of palladium or of any other metal.

In prior cross bar switches, it has been customary to make the contact members of palladium backed up by a cheaper metal such as a piece of nickel silver, the nickel silver constituting, with the palladium, a bi-metallic strip welded as a unit to the conductor, this bi-metallic strip being necessary in the prior construction in order to secure enough height to insure good contact and proper operation. It will be noted that in FIG. 1 of my Patent 2,729,706 that the contact-carrying tongues of the link bar are flat tongues lying in the same plane as the top of the inverted channel bar and that the same construction is present in my prior Patent 2,731,516 as shown in FIG. 5 thereof. Because of this construction, the contact members 9d and 11d of Patent Nos. 2,729,706 and 2,731,516, respectively, had to be built up to a substantial height to insure satisfactory contact.

In the construction of the present application, however, the contact members 103 and 105 are carried by spring tongues 107 and 109 which themselves incline upwardly from the plane of the normal top surface of the link bars 67, so it is no longer necessary to make the contact members themselves so thick. The ability to use thinner contact members of gold or palladium only, instead of thicker members of palladium backed up by nickel silver alloy, makes for a material saving in costs.

For an individual lead-out arrangement, channel bars 367 (FIG. 4) may be used corresponding in general to short sections of the channel bars 67. Each channel bar 367 has a pair of spring fingers 107, 109 identical with those previously described and having contact pieces 103, 105 thereon, such as previously described. Each section 367 is connected to a conductor leading to an individual terminal. At one end each depending flange of each channel member 367 has a small ear 375 by which it may be connected to the conductor.

While the invention has been described in connection with a specific embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth, and as fall within the scope of the invention or the limits of the appended claims.

Having thus described my invention, what I claim is:

1. The method of forming an electric switch contact member having a pair of resilient aligned tongues, which comprises the steps of subjecting a strip of beryllium copper having an approximately plane portion, from which the tongue are to be formed, to a punching operation to sever the side edges of the tongues from the rest of the strip and to arch the two tongues together out of the plane of the strip without completely severing the adjacent ends of the two tongues from each other, heat treating the strip to relieve stresses therein and to harden the strip while the tongues remain arched and integrally connected to each other so that the arched condition of the connected tongues will tend to maintain them in intended position without warpage during heat treatment, and then severing the adjacent ends of the two tongues from each other after the conclusion of the heat treatment.

2. The method as defined in claim 1, further including the step of securing electric contact portions of gold

to the tongues after the conclusion of heat treatment and after the two tongues are severed from each other.

3. The method of forming an electric switch contact member having a pair of resilient aligned tongues, which comprises the steps of subjecting a strip of beryllium copper having an approximately plane portion to a punching operation to sever the side edges of the tongues from the rest of the strip and to arch the two tongues together out of the plane of the strip while partially severing the adjacent ends of the two tongues from each other, heat treating the strip to relieve stresses therein and to harden the strip while the tongues remain arched and integrally connected to each other so that the arched condition of the connected tongues will tend to maintain them in intended position without warpage during heat treatment, and then, after the conclusion of the heat treatment, completing severing of the adjacent edges of the two tongues from each other.

4. The method of forming an electric switch contact member having a pair of resilient aligned tongues, which comprises the steps of subjecting a strip of beryllium copper having an approximately plane portion from which the tongues are to be formed to a punching operation to sever the side edges of the tongues, to arch the two tongues together out of the plane of the strip, and to partially sever the adjacent ends of the tongues from each other while leaving a bridge of metal narrower than the width of said adjacent ends of the tongues integrally connecting the tongues together, heat treating the strip to relieve stresses therein and to harden the strip while the tongues remain arched and integrally connected to each other so that the arched condition of the connected tongues will tend to maintain them in intended position without warpage during heat treatment, and then, after conclusion of the heat treatment, subjecting the bridge to a twisting operation to sever the bridge from the adjacent ends of the tongues and to sever the two tongues from each other.

5. The method as defined in claim 4, wherein the steps of heat treating the strip comprises heating it to approximately 700° F. and holding it at said temperature for approximately one hour and then allowing it to cool slowly.

6. The method as defined in claim 4 wherein the heat treating step comprises heating the strip to 600° F. and then holding it at that temperature for approximately two hours and then allowing it to cool slowly.

7. The method of forming an electric switch contact member, which comprises subjecting a strip of metal to a punching operation to stamp up and partially sever from said strip an elongated arched portion connected at its opposite remote ends to the strip, stress-relieving and hardening the strip while said portion remains arched and integrally connected at both ends to the strip, and then cutting the arched portion transversely midway of its length to form two resilient tongues whose adjacent ends face toward each other and lie in the same plane.

8. The method of forming an electric switch contact member according to claim 7, further including the step of securing two electric contact portions of a different metal from the metal of said strip at opposite sides of the longitudinal center of the strip after the conclusion of stress-relieving and hardening and after cutting the arched portion, the contact portions being secured, respectively, to the two tongues formed by the cutting operation.

9. The method of forming an electric switch contact member, which comprises subjecting a strip of metal to a punching operation to stamp up and partially sever from said strip an elongated arched portion which is connected at its distal ends to the strip, and which is of gradually decreasing width from each of said ends toward the center of the arched portion, and partially severing the central portion of said arched portion from the remainder of said arched portion along parallel lines

extending part-way from opposite lateral sides of the arched portion inwardly, thereby to leave a short-length narrow bridge portion at the center of the arched portion, heat-treating the strip while said arched portion remains arched and integrally connected at its distal ends to the strip, and then severing the bridge portion from the arched portion to form two resilient tongues whose adjacent ends face toward each other.

10. The method of forming an electric switch contact member according to claim 9, further including the step of securing two electric contact portions of a different metal from the metal of said strip at opposite sides of said bridge portion after the conclusion of the heat treatment and after severing the bridge portion, the contact portions being so separated from one another that, after 15 severing of the bridge portion, the contact portions are secured to adjacent ends of the two tongues formed.

11. The method of forming an electric switch as claimed in claim 9, wherein the bridge portion is severed from the rest of the arched portion by a twisting operation effected by moving two punch tools toward each 20

other from above and below the arched portion, respectively, to move the part of the arched portion which is at one side of said bridge portion downwardly while moving the part of the arched portion which is at the other side of said arched portion upwardly to twist the bridge portion loose from said two parts of the arched portion.
